BOX STACKING APPARATUS

Ambrose A. Neja, Anaheim, Calif.

Application December 6, 1947, Serial No. 790,117

20 Claims.

(Cl. 214—6)

1

This invention relates to a box stacking apparatus.

The general object of the invention is to provide a box stacking apparatus including novel means for placing boxes fed singly and horizontally into a stack one upon the other.

A more specific object of the invention is to provide a box stacker including novel means for lifting and for supporting boxes to form a stack.

A further object of the invention is to provide a box stacker including novel means for feeding boxes to a stack.

Another object of the invention is to provide a box stacker including novel means for discharging a stack of boxes.

A further object of the invention is to provide a box stacker including novel means for lifting boxes.

A further object of the invention is to provide a box stacker including novel means for supporting a box after it has been lifted.

Another object of the invention is to provide a box stacking apparatus including a novel table for receiving the stacked boxes.

Another object of the invention is to provide a novel means for controlling the operation of a box stacker.

Other objects and advantages of my invention will be apparent from the following description taken in connection with the accompanying drawings, wherein:

Fig. 1 is a side elevation view of my improved box stacker;

Fig. 2 is a front elevation view of the box stacking mechanism;

Fig. 3 is a top plan view of the box stacking and conveying mechanism;

Fig. 4 is a fragmentary sectional view taken on line 4—4 of Fig. 2, showing part of the feed conveyor and roller table support;

Fig. 5 is a fragmentary rear view, showing details of the conveying mechanism;

Fig. 6 is a sectional view taken on line 6—6, of Fig. 5;

Fig. 7 is a sectional detail taken on line 7—7 in Fig. 6, showing my improved safety stop mechanism;

Fig. 8 is a sectional detail taken on line 8—8 in Fig. 6, showing the arrangement for positively introducing boxes into the stacker;

Fig. 9 is a sectional view taken on line 9—9 of Fig. 2, showing parts in elevation;

Fig. 10 is a sectional view of the lifting and supporting mechanisms taken on line 10—10 of Fig. 9, with parts in different relative positions;

2

Fig. 11 is a view similar to Fig. 10 taken generally on line 11—11 of Fig. 9, with parts further disposed in different positions;

Fig. 12 is a sectional view taken on line 12—12 of Fig. 1 and showing details of the box supporting mechanism;

Fig. 13 is a sectional view showing one of the timing switches, taken on line 13—13 of Fig. 2;

Fig. 14 is a view similar to Fig. 13, showing another timing switch and taken on line 14—14 of Fig. 2;

Fig. 15 is a wiring diagram for the box stacking and conveying mechanism;

Fig. 16 is a sectional view taken as indicated generally by line 16—16 in Fig. 3, and

Fig. 17 is an enlarged, fragmentary view taken substantially on line 17—17, Fig. 2.

Referring to the drawings by reference characters, I have shown my invention as embodied in a box stacking and handling apparatus which is indicated generally at 10. As shown, the apparatus includes a frame 11, feed conveying apparatus 12, driving means 13, box elevating means 14 to raise individual boxes to a stacked position, support means 15, adapted to support stacked boxes, and discharge conveying means 16 to convey a stack of boxes away from the stacker.

The frame 10 as shown includes spaced vertical front members 17 and 18, rear members 19 and 20, a base front tie member 21 and a similar rear tie member 22. Angle members 23, 24, 25 and 26 connect the tops and bottoms of the members 17, 18, 19 and 20. An angle cross member 27, disposed intermediate the length of angle members 19 and 20, supports a pair of spaced tubular guides 28 and 29. The top extremities of the guides 28 and 29 are connected by a tubular cross member 30. The cross member 30 supports a depending tubular guide 31. The lower end of the guide member 31 rests on a plate 31' fixed to a cross member 19' connecting the upper ends of the uprights 19 and 20. Extending rearwardly from and rigidly fastened to the cross member 27, I arrange a pair of angle supports 32 and 33, the outer ends of which are supported by braces 34 and 35.

The upper ends of the braces 34 and 35 are secured to the cross member 19' as shown at 36, Fig. 1. Adjacent the base of the apparatus I arrange a pair of supporting angle members 37 and 38. These latter angles are attached to the vertical frame members and form a support by which the apparatus may be bolted to the floor. The structure remaining below these last mentioned angles may be recessed into the floor.

The feed conveying apparatus 12 (Figs. 3, 5 and 6) includes a pair of delivery chains 39 engaging sprockets 40 arranged on a shaft 41. The shaft 41 is journaled in bearing blocks 42 fixed to spaced angle members 43 and 44. The angle 43 supports a switch 45, adapted to be actuated by an incoming box through an arm 46 pivoted at 47. Between the side member 37 and the angles 43 and 44 I arrange a pair of supporting plate members 48 and 49 which support shafts 49 for rollers 50, 51, 52 and 53.

The first roller 50 is divided in the center and has a box engaging stop arm 55 (Fig. 7) rotatably supported on a reduced roller 56 intermediate the length of this roller. The portion 56 has a downwardly depending arm 57 adapted to be engaged between two stops 58 and 59 on an arm 60 fixed upon a shaft 61 which is journaled in bearing blocks 62 fixed to the side members 48 and 49. The shaft 61 has a dependent arm 63 fixed thereto as at 64. This arm 63 slidably supports a rod 65 (Fig. 5, Fig. 6 and Fig. 7), one end of which is provided with a spring 66. The other end of the rod 65 engages one arm of a bell crank 67 which is supported at its lower end to a pivot 68. The other arm of the bell crank extends upwardly as at 70. A spring 71, fixed to a web 72, normally urges the lever 70 and the rod 65 to an inward position as shown in Fig. 6.

A switch 73 is fastened to the web 72 and is adapted to be actuated by the arm 70. Thus it may be seen that a box entering upon the rollers 50 to 54 will strike the lever 70, actuating the switch 73 and moving the rod 65 to turn the shaft 61, thus moving the arm 60 to a position as shown by the dotted lines in Fig. 7 so that the stops 58 and 59 will confine the arm 57 and prevent movement of the stop arm 55 to thus prevent another box from crowding in upon the first box. A spring 74 attached to one end of the arm 60 aids in lifting the arm.

The rollers 50 and 52 are driven by a motor 75 through chains 76 and 77 and 78 and sprockets 79 and 80. The motor 75 is controlled by the switches 45 and 73 and drives the rollers 50 and 52 continuously until another box moves up on the incoming conveyor, thereby depressing lever 46 and opening switch 45.

Arranged between the plates 48 and 49 and supported thereby, I provide a pair of spaced chain guides 82 and 83. These chain guides, as shown in Fig. 4, include a horizontal upper portion 83a, a horizontal bottom portion 83b and an inclined end portion 83c. The construction is such that a tip 83d which advances the chain close to rollers to be presently described is provided. Over the chain guides delivery chains 84 and 85 operate and these are supported at the point opposite the chain guide tip 83d by sprockets 86 and 87 which are arranged on a shaft 88 journaled in bearing blocks 89 and 90 fixed to supports 91 and 92, which in turn are attached to the plate 49.

One end of the shaft 88 supports a sprocket 95, fitted with a chain 96 which is adapted to be driven by a sprocket 97 supported by a shaft 98 journaled in bearing blocks 99 and 100. Bearing block 99 is fixed to the side angle member 47 and bearing block 100 to the outer end of a clutch support frame 101, the inner end of which is fixed to the angle member 37.

The shaft 98 also supports a sprocket 104 for a drive chain 105 driven by a sprocket 105' on a motor 106. A clutch mechanism 107 of conventional design is fixed to the shaft 98 and is

adapted to be operated by a solenoid 108 by means of a lever 110 supported by an arm 111, fixed to the support frame 101. The motor 106 is adapted to run continuously and be caused at the proper time, by the clutch 107, to drive the sprocket 97, chain 96, sprocket 95 and in turn delivery chains 84 and 85. The chains 84 and 85 include aligned pairs of special links 115 as shown in Fig. 8, which support cylindrical box engaging members 116 and 117. The links 115 are located in spaced relation on the chains 84 and 85.

A pair of box retarding members 120 and 121 (see Figs. 4 and 6) are pivotally supported as at 122 and 123 to the chain guides 82 and 83 and each has depending arms 124. Spring 125, extending from the arms 124 and the plate 48, serve to retain the guides in the position shown in Fig. 4. Incoming boxes are adapted to pass over these members 120 and 121, depressing them. When the boxes have passed the members they move upwardly and prevent reverse movement of the box.

The driving means 13 (see Fig. 1) includes a motor 130, fitted with a conventional brake mechanism 131 (Fig. 2) to quickly stop the apparatus at a desired point. The motor 130 drives a shaft 132 which has a sprocket 133 thereon. The sprocket 133 drives a chain 134 which drives a sprocket 135 fixed on a shaft 136. The shaft 136 is journaled in bearing blocks 137 and 138, fixed to the braces 34 and 35. The outer ends of the shaft 136 are fitted with crank arms 139 and 140, the ends of which pivotally support at 140a one end of chains 141 and 142. The chains 141 and 142 run over sprockets 143 and 144, fixed to shafts 145 and 146 journaled in bearing blocks 147 and 148.

The other ends of the chains 141 and 142 are attached as at 150 (see Fig. 9) to the box elevating means 14 which includes opposed sliding plates 160 and 161, disposed respectively between forward upright angle member 17 and rear member 19 and forward upright angle member 18 and rear member 20. The mechanism on the two sides of the machine is complementary and therefore only the left side is shown in detail and will be described. A pair of bearing blocks 162 and 163, fixed to the plate 160, journal a shaft 164 which pivotally supports a pair of box engaging arms 165 and 166. The lower ends of the arms 165 and 166 are provided with lips 167 which are adapted to engage the bottom of a box.

The upper end of the arm 166 is fitted with a rod 168 (Fig. 9) which extends rearwardly through an opening 169 in the plate 160 (Fig. 9) and has an enlarged end 170 thereon. A spring 171, arranged about the rod 168 between the enlargement 170 and the plate 160, normally urges the arms 165 and 166 to the position shown in Fig. 2.

The upper end of engaging arm 165 is slightly longer than the upper end of arm 166 and is also fitted with a rod 172 (Figs. 9 and 10) which extends rearwardly through an opening 173 in the plate 160 and is journaled in a sliding bearing 174 and is terminated by an enlargement 175. A spring 176, arranged about the rod 172 between the bearing 174 and the enlargement 175, cooperates with the before-mentioned spring 171 about the rod 168. The bearing 174 is fixed to the midportion of an arm 178 which is pivotally supported as at 179 to a bearing block 180 fixed to the rear side of the plate 160. The upper end of the arm 178 is fitted with a

roller 182, the function of which will be later described.

The plate 160 is fitted at each corner thereof with rollers 185 (see Fig. 1) which are supported on shafts 185'. The rollers are adapted to roll on tubular guides 186 and 187 which are fixed to the top angle member 23 and the bottom member 24.

Arranged between the top angle member 23 and a side brace 190, I provide a cam support 191 (see Figs. 1 and 2) which supports a cam surface plate 192 which is adapted to control the movement of the roller 182. Adjacent the upper end of the cam plate 192 and pivotally supported as at 193, I arrange a cam guide arm 194 having an inclined upper surface 196 which is a continuation of the inclined upper surface 196a on the cam plate 192.

A spring 197 (Fig. 1) about the pivot 193 normally urges the arm 194 to the position shown in Fig. 10 where the arm engages a stop 198 (Fig. 1) on the cam support 191. Thus it may be seen that upon upward travel of the roller 182 it will strike against the lower inclined surface 195 of the arm 194, moving arm 194 anti-clockwise to the position shown by dotted lines in Fig. 10. While the roller is at the top of its movement the arm 194 will return to its normal position and as the roller 182 descends it will be guided by the beveled edges 196 and 196a to thus travel, on the downward stroke, against the forward face of the cam plate 192, moving the box engaging arms 165 and 166 to a position shown by the dotted lines in Fig. 10 so that they may pass across the ends of a box to later snap in beneath the box preparatory to raising the box to a stacked position.

The support means 15, adapted to support boxes as the stack is being formed, is also symmetrical on both sides of the apparatus and includes a plate 200 (see Fig. 9) located directly below the plates 160 and 161 but on the opposite sides of the tubular guides 186 and 187. The plate 200 is similarly fitted with rollers 201, adapted to engage and be guided by the guides 186 and 187. A pair of bearing blocks 202 and 203 are attached to the plate 200 and journal a shaft 204 about which are mounted supporting arms 205 and 206. The upper ends of the arms 205 and 206 are connected by a cross member 207 (see Fig. 12). The cross member has an inwardly directed horizontal ledge 208 which is adapted to receive and support the lowermost box of a stack of boxes.

A rod 209 is pivotally supported at one end as at 210 (Fig. 12) to the arm 205, the other end of the rod being journaled in a guide 211, mounted on an upright frame member 212. A pin 213 limits the inward travel of the rod 209. A spring 214 about the rod 209 normally urges the rod, and thus the arms 205 and 206, to the position shown in Fig. 12.

A limit switch 215 (Fig. 1), the action of which will be later described, is mounted on the upright frame member 19 and is adapted to be actuated by a cam 216 fixed to the rear face of the plate 200.

A timing mechanism, indicated generally at 220 (see Figs. 1 and 17), is provided. The mechanism includes a plate 226, having a series of projecting pegs 227 fitted thereto. One of the pegs 228 is slightly longer than the others for a reason to be later described. The plate 226 is mounted on a shaft 229, journaled in bearing block 230 mounted on the upright 19. The plate

is held against undue rotation by a catch 231, pivotally supported as at 232 and normally urged to the position shown in Fig. 1 by a spring 233. A dog support 234 (see Figs. 1, 11 and 17), fixed to the shafts 185' which support the rollers 185 on the plate 160, pivotally supports a dog 235 which is adapted to engage and move one of the pegs 227 to move the timer plate 276 step-by-step to the next position. When the longer peg 228 comes into correct position, it is adapted to strike cam surface 238 of a lever 239, fixed to a shaft 240, journaled in bearing blocks 241 on the uprights 19 and 20 (see Fig. 1), and raise arms 242, secured on the shaft 240, thus releasing the end 243 of the arm 242 from engagement with a lever 244, which is pivotally supported as at 245 to the cam support 191. A grooved roller 246, rotatably supported on the plate 160, serves as a guide for the arm 244. When the arm 242 is moved a lever 247 actuates a switch 248 mounted on the upright 19. A lever 250 connects the arm 244 with the plate 200 and thus it may be seen that the lever 244 having been disengaged from the arm 242, on the downward stroke of the plate 160, as shown by the dotted lines of Fig. 9, and guided by the roller 246, will move to a position shown by dotted lines in Fig. 1 and through the lever 250 will lower the plate 200 to a position as shown by the dotted lines in Fig. 9.

Pivotally mounted as at 255 and 256 to supports 257 and 258, which are in turn attached to front and rear tie members 21 and 22, I arrange a pair of table lifting and lowering arms 259 and 260. In their uppermost position, as shown in Fig. 9, the inner ends of the arms 259 and 260 are adapted to be supported by a pin 261, secured by means of a bracket 262 to the plate 200. Intermediate the support 261 and the pivots 255 and 256, I arrange on the arms 259 and 260 a pair of table supporting shafts 263 and 264. The shaft 263 is fitted to support bearings 265 which in turn are fixed to the forward end of a frame 266 of a box supporting table. The rear shaft 264 supports the rear of the frame 266. The frame 266 is fitted with a brace 267 and rotatably supports a series of rollers 268 which are adapted to receive an incoming box from the chains 84 and 85.

Thus it may be seen that upon downward movement of the plate 200, the support pin 261 will descend to lower the inner ends of the arms 259 and 260 and will lower the table to a position shown in Fig. 11 and thus allow a completed stack of boxes to be engaged by the outgoing conveying mechanism 16.

A pair of box stops 270 and 271 (Fig. 3) are fixed to the shaft 263 adjacent the forward end of the table frame 266. Also attached to the shaft 263 at the central portion thereof, I arrange a lever 272 which is held in position by a shaft 273 journaled in a frame 274, pivotally mounted as at 275 to the front angle member 21. A spring 276 normally urges the shaft 273 into the position shown in Fig. 3. An arm 277, fixed to the forward end of the shaft 273 and guided by a section of the frame 274, is adapted to actuate a switch 278 when the shaft 263 is rocked when a box strikes the stops 270 and 271 and shifts the lever 272.

When the table is in lowered position, the lever 272 is brought out of engagement with the rod 273, thus allowing the shaft 263 to pivot and lowering the stops 270 and 271 to a position as shown in Fig. 11 to allow the stack to move out

of the apparatus. A spring 279 returns the stops 270 and 271 to their normal position after the stack has passed them.

The outgoing conveying mechanism 16 consists of a pair of chains 280 and 281 (see Figs. 3 and 6) operating over inner sprockets 282 and 283, which are in turn rotatably mounted on the outer sides of the chain guides 82 and 83. The outer ends of the chains 280 and 281 are secured to outer sprockets 284 and 285, mounted on a shaft 286 journaled in bearing blocks 287 and 288, which are secured to bearing supports 289 and 290, secured to the angle 21. The chains 280 and 281 are supported on their upper side by chain guides 291 and 292.

Also mounted on the shaft 286, I arrange a stack transfer mechanism (see Fig. 3) which consists of three chains 293, their outer ends being rotatably mounted on sprockets fixed to a shaft 294 which is journaled in bearing blocks 295 and 296 which may in turn be fixed to the floor on which the apparatus is mounted. The center chain is adapted to support the center of the bottom box of the stack to prevent the breaking of the bottom of this box by the inwardly moved outer chains until the stack can be transferred to the larger conveyor chains 297 and 298 which are also secured by means of sprockets 299 to the shaft 294. A motor 300 is adapted to drive the chains 280 and 281, the transfer chains 293 and the larger final conveyor chains 297 and 298, all of which may operate continually.

A limit switch 301 (Fig. 3) is fixed to the angle 21 and has an arm 302 which extends outwardly and upwardly and is adapted to be actuated by an outgoing stack of boxes.

In the event the apparatus should attempt to stack more than the desired number of boxes, nine in the combination shown, the top box will strike a lever 310 (see Fig. 1), pivotally supported as at 311 to a support 312 which is mounted on the cross member 38 of the guides 28 and 29. The lever 310 is fixed to a rod 313 which extends downwardly and has an arm 314 thereon. The arm 314 is fitted with a spring 315 which is adapted to actuate a switch 316, mounted on a support 317 which is in turn fixed to the frame 11. The lower end of the rod 313 is fixed to a safety arm 318 which is in turn pivotally supported as at 319 to the angle cross members 27. In the event a box should become broken or if a box should not fully enter the machine and the apparatus should start to attempt to stack such a box, the lever 318 would be contacted, thus raising the rod 313 and actuating the switch 314 to cut off the power to the entire machine.

Fixed to the brace 34, I arrange a pair of switches 320 and 321 (see Figs. 2 and 3). The switch 320 is adapted to be actuated by a timer arm 322 fixed to the shaft 136, while the switch 321 is adapted to be actuated by a cam 323, also fixed to the shaft 136. The brace 35 supports a third switch 325 which is adapted to be actuated by timer arms 326 and 327, fixed to the shaft 136. It may be seen that the switches 320, 321 and 325 operate in connection with the raising and lowering of the plate 160 as the mechanism used in this operation is also fixed to the shaft 160.

In operation of the apparatus, a box being conveyed by the chains 39 is delivered thereby onto the rollers 50, 51, 52 and 53. The box strikes the lever 70, closing one side of the switch 73, thus energizing the clutch solenoid 108 and starting movement of the chains 84 and 85. One of the box engaging members 116 or 117 moves the box

into the stacker and through the stops 270 and 271 and the lever 272 closes the switch 278, which starts operation of the main drive motor 130, which latter, through chains 134, cranks 139 and 140 and chains 141 and 142, lowers the plate 160. The roller 132 moves along the cam plate 192 to place the arms 165 and 166 in position to engage and pick up the box. The arms 165 and 166 then engage a box, raising it. As the box rises, the cross members 201 are pushed out of the path until the box is high enough to be engaged by the ledge 208, whereupon the cross members move inward in position so that the lower ends of the box are engaged. The apparatus continues to operate and when a half revolution has been made and the plate 160 is in its lower position, switch 325 is opened but the circuit remains complete through switch 321 and switch 248. When the eighth box is lifted, the longer peg 228 of the timing plate 226 strikes the cam surface 238 of the lever 239, and, as previously described, moves the end 243 of the arm 242 out of engagement with the lever 294. At the same time the lever 241 opens one side of the switch 248, closing the other side of the switch and putting it in the circuit to continue the operation of the motor 130. The cam 323 again opens switch 321, stopping the machine at the top of the stroke.

The ninth box is then delivered to the apparatus, closing switch 73, and as the plate 160 descends, through the lever 244 and the arm 250, the lower plate 200 is also caused to descend, lowering the table frame 266. As the plate 160 descends, the rod 204, being fixed at its outer end, moves the box supporting means 15 out of engagement with the stack, permitting the stack to be lowered onto the ninth box after which the complete stack is conveyed by chains 280 and 281 away from the machine. When the stack has cleared the machine it engages the lever 302, closing the switch 301, starting the motor 130 to put the apparatus back into position to start the next stack.

Switch 45 is connected in series with switch 73 to stop incoming chains in the event of a second box coming onto the initial conveyor before the first has been moved into the stacker. Another safety switch 215 is opened when the plate 200 is in its down position to prevent a box 50 coming into the apparatus before the stack is moved away. When the boxes one to eight are being stacked, switch 320 performs the same function as switch 215.

Referring now primarily to the schematic wiring diagram of Fig. 15, electrical current is brought to the machine through leads 350 and 351 through a master switch 352. Emergency switch 316 is normally closed and by means of lead 353 connected to one side of the switch 60 316, and lead 354 connected to lead 353, and lead 355 connected to lead 350, the motor 106 is continuously operated. Lead 356, connected to lead 353, and lead 357, connected to lead 350, maintain the motor 300 in constant operation.

Motor 75 is maintained in continuous operation through switch 73 and lead 358, lead 359 and lead 360 and when switch 73 is opened through switch 45, which acts as an emergency switch, preventing a box from entering upon the table 266 when another box is already there.

When the lever 70 is depressed, switch 73 is moved, allowing current to flow through leads 361 and 362 to switch 215 and through lead 363 to switch 320 and thereby through lead 364 to solenoid 108, the circuit being completed by lead

365, connected to lead 350, causing the core of solenoid 108 to be moved to engage the clutch 107 and causing the motor 106 to drive the mechanism.

When a box moves onto the table 266 the switch 278 is closed, allowing current to flow through leads 366 and 367 to the motor 130, the circuit being completed by lead 368 connected to lead 350, causing the motor 130 to start. While the closing of switch 278 is only momentary, power is continued to be supplied to the motor 130 through switch 321, closed by the movement of the cam 323 from the switch roller.

From switch 321 current flows through lead 368 to switch 248 and through lead 369 to lead 361 to the motor 130. Switch 248 is opened only after the stacking of the last box. The switch 325 is then opened and the motor 130 stopped. The passing of the stack over lever 302 closes switch 301, allowing current to flow through leads 370, 371, 372, 373 and into 367 to again start motor 130 to return the machine to its original position to start another stack.

When switch 301 is open current may pass from lead 371 to lead 372 through switch 325 and lead 374, which is connected to 367, to keep motor 130 in operation. The machine having returned to its original position is now ready to receive another series of boxes to be stacked.

Having thus described my invention and the present preferred embodiments thereof, I desire to emphasize the fact that many modifications may be resorted to in a manner limited only by a just interpretation of the following claims, wherein I claim:

1. In a box stacking apparatus, a box stacking station, means for moving a box to the station, stack supporting means mounted to move to and from supporting position, means urging said stack supporting means to supporting position, box lifting means at said station and operable to lift a box to a position to be engaged by the supporting means, means to cause said lifting means to release a box when in position to be engaged by the supporting means and to return to box receiving position, means to cause said lifting means to repeatedly operate until a desired number of boxes has been stacked, one beneath the other, a discharge conveyor, means operable to place the lowermost box of a stack on the discharge conveyor and means to cause said stack supporting means to move to box releasing position to permit the previously formed stack of boxes to be deposited on the said lowermost box.

2. In a box stacking apparatus, a box stacking station, means for moving a box to the station, stack supporting means mounted to move to and from box supporting position, means urging said stack supporting means to box supporting position, box lifting means at said station and operable to lift a box to a position to be engaged by the supporting means, means to cause said lifting means to release a box when in position to be engaged by the supporting means, means to cause said lifting means to repeatedly operate until a desired number of boxes has been lifted and stacked, one upon the other, and means to cause said stack supporting means to move to releasing position to permit the previously stacked boxes to be deposited on a box below the stacked boxes.

3. In a box stacking apparatus, a box stacking station, means for moving a box to the station, stack supporting means mounted to move to and from box supporting position, means urging said stack supporting means to supporting position,

box lifting means mounted adjacent to said station and operable to lift a box at the station to a position to be engaged by the supporting means, means to cause said lifting means to release a box when in position to be engaged by the supporting means, timing mechanism to cause said lifting means to repeatedly operate until a desired number of boxes has been stacked, a discharge conveyor disposed adjacent to said table and adapted to receive a stack of boxes, said timing mechanism including means operable to place the lowermost box of a stack on the discharge conveyor and means to cause said stack supporting means to move to releasing position to permit the previously stacked boxes to be deposited on the said lowermost box.

4. In a box handling apparatus, spaced feed conveyor chains, means to drive said conveyor chains, a set of box conveying rollers adjacent to said feed conveyor and adapted to receive boxes from said feed conveyor chains, a box stacking station adjacent to and at one side of said rollers, a pair of spaced plates at said station, means to mount said plates for vertical reciprocation, a stack supporting frame supported by said plates, a set of rollers on said frame, spaced chains adjacent to said first set of rollers, said chains being disposed at right angles to said first mentioned chains, means carried by said second pair of chains for engaging a box on said first set of rollers and for moving said box axially along the first set of rollers onto the second set of rollers, means for lifting a box on said second set of rollers and means carried by said plates for supporting a box lifted by said lifting means.

5. In a box stacking apparatus, a box supporting table, means for moving a box onto the table, box lifting means mounted adjacent to the table and adapted to engage and lift a box on the table, means to operate said lifting means, stack supporting means mounted to move to and from box supporting position, means urging said supporting means to box supporting position, means to cause said lifting means to release a box when in position to be engaged by the supporting means, timing mechanism to cause said lifting means to repeatedly operate until a desired number of boxes has been stacked, a discharge conveyor disposed adjacent to said table and adapted to receive a stack of boxes, said timing mechanism including means operable when the lowermost box of a stack has been placed in position on the table to cause relative vertical movement between the table and the discharge conveyor to place said lowermost box on the discharge conveyor and means to cause said stack supporting means to move to releasing position to permit the stacked box to engage the box thereunder.

6. In a box stacking apparatus, a box supporting table, means for moving a box onto the table, stack supporting means mounted to move to and from box supporting position, means urging said stack supporting means to box supporting position, box lifting means mounted adjacent to said table and operable to lift a box from said table to a position to be engaged by the supporting means, means to cause said lifting means to release a box when in position to be engaged by the supporting means, timing mechanism to cause said lifting means to repeatedly operate until a desired number of boxes has been stacked, a discharge conveyor disposed adjacent to said table and adapted to receive a stack of boxes, said timing mechanism including means operable when a

11

box which is to be the lowermost box of a stack has been placed in position on the table to cause relative vertical movement between the table and

12

charge conveyor chains disposed below said table and adapted to receive a stack of boxes, said timing mechanism including means for operat-

means to engage the end of a box at the stacking station, means to alternately raise and lower said lifting arms, means mounting said arms for movement towards and from each other, means normally urging said arms to box engaging position at the bottom of their travel, cam means causing said arms to separate at the upper limit of their movement, a pair of stack supporting arms pivotally mounted on said table mounting means, means urging said last mentioned arms to box engaging position, means whereby said supporting arms are separated by an ascending box passing therebetween, timing mechanism operable step by step to cause said lifting arms to reciprocate until a desired number of boxes has been stacked, discharge conveyor chains at the stacking station and disposed below said table and adapted to receive a stack of boxes, said timing mechanism including means operable when the lowermost box of a stack has been placed in position on the table to cause downward movement of the table mounting means to lower said last placed box onto the discharge conveyor chains, and means to cause said stack supporting arms to be withdrawn from beneath the stacked boxes to cause the stack to descend onto the box thereunder.

13. In a box stacking apparatus, a box stacking station, a box supporting table at said station, means to mount said table for vertical reciprocation, means for moving a box onto the table, a pair of lifting arms, means to reciprocally mount said lifting arms at each end of a box on the table, each of said arms having an inwardly directed lip adapted to engage beneath a box at the stacking station, means to alternately raise and lower said lifting arms, means mounting said arms for movement towards and from each other, means normally holding said arms in box engaging position at the bottom of their travel, cam means causing said arms to separate at the upper limit of their movement, a pair of stack supporting arms pivotally mounted on said table mounting means, means urging said last mentioned arms to box engaging position, means whereby said supporting arms are separated by an ascending box passing therebetween, timing mechanism operable step by step to cause said lifting arms to reciprocate until a desired number of boxes has been stacked, discharge conveyor chains at the stacking station and disposed below said table and adapted to receive a stack of boxes, said timing mechanism including means operable when the lowermost box of a stack has been placed in position on the table to cause downward movement of the table mounting means to lower said last placed box onto the discharge conveyor and means to cause said stack supporting arms to be withdrawn from beneath the stacked boxes to cause the stack to descend onto the box thereunder.

14. In a box stacking apparatus, a box stacking station, a box supporting table at said station, means to mount said table for vertical reciprocation, means for moving a box onto the table, a pair of lifting arms, means to reciprocally mount said lifting arms at each end of a box on the table, each of said arms having an inwardly directed lip adapted to engage beneath a box at the stacking station, means to alternately raise and lower said lifting arms, means mounting said arms for movement towards and from each other, means normally holding said arms in box engaging position at the bottom of their travel, cam

means causing said arms to separate at the upper limit of their movement, a pair of stack supporting arms pivotally mounted on said table mounting means, means urging said last mentioned arms to box engaging position, timing mechanism operable step by step to cause said lifting arms to reciprocate until a desired number of boxes has been stacked, discharge conveyor chains at the stacking station and disposed below said table and adapted to receive a stack of boxes, said timing mechanism including means operable when the lowermost box of a stack has been placed in position on the table to cause downward movement of the table mounting means to lower said last placed box onto the discharge conveyor and means operated by downward movement of said mounting means to cause said stack supporting arms to be withdrawn from beneath the stacked boxes to cause the stack to descend onto the box thereunder.

15. In a box stacking apparatus, a box stacking station, a pair of supporting plates at said station, means to mount said plates for vertical reciprocation, a stack supporting frame supported by said plates, a set of rollers on said table forming frame, means for moving a box axially onto the table forming rollers, a pair of lifting arms, means to reciprocally mount said lifting arms at each end of a box at the stacking station, each of said arms having an inwardly directed lip adapted to engage beneath a box at the stacking station, means to alternately raise and lower said lifting arms, means mounting said arms for movement towards and from each other, spring means normally holding said arms in box engaging position at the bottom of their travel, cam means causing said arms to separate at the upper limit of their movement, a pair of stack supporting arms pivotally mounted on said supporting plates, means urging said last mentioned arms to box engaging position, means whereby said supporting arms are separated by an ascending box passing therebetween, timing mechanism operable step by step to cause said lifting arms to reciprocate until a desired number of boxes has been stacked, discharge conveyor chains at the stacking station and disposed below said table rollers and adapted to receive a stack of boxes, said timing mechanism including means operable when the lowermost box of a stack has been placed in position on the table rollers to cause downward movement of the first set of plates to lower said last placed box onto the discharge conveyor and means operated by downward movement of said first pair of plates to cause said stack supporting arms to be withdrawn from beneath the stacked boxes to cause the stack to descend onto the box thereunder.

16. In a box stacking apparatus, a box stacking station, a pair of supporting plates at said station, means to mount said plates for vertical reciprocation, a stack supporting table supported by said plates, means for moving a box onto the table, a pair of lifting arms, means to reciprocally mount said lifting arms at each end of a box at the stacking station, said arms having inwardly directed lips adapted to engage beneath a box at the stacking station, means to alternately raise and lower said lifting arms, means normally holding said arms in box engaging position at the bottom of their travel, means causing said arms to separate at the upper limit of their movement, stack supporting arms pivotally mounted on said supporting plates, means normally urging said last mentioned arms to box

engaging position, means whereby said supporting arms are separated by an ascending box passing therebetween, timing mechanism operable step by step to cause said lifting plates to reciprocate until a desired number of boxes has been stacked, discharge conveyor means at the stacking station and disposed below said table and adapted to receive a stack of boxes, said timing mechanism including means operable when the lowermost box of a stack has been placed in position on the table to cause downward movement of the first set of plates to lower said last placed box onto the discharge conveyor and means to cause said stack supporting arms to be withdrawn from beneath the stacked boxes to cause the stack to descend onto the box thereunder.

17. In a box stacking apparatus, a box stacking station, a pair of supporting plates at said station, means to mount said plates for vertical reciprocation, a stack supporting frame supported by said plates, a set of rollers on said table forming frame, means for moving a box onto the table forming rollers, a pair of lifting arms, means to reciprocally mount said lifting arms at each end of a box at the stacking station, said arms having inwardly directed lips adapted to engage beneath a box at the stacking station, means to alternately raise and lower said lifting arms, means normally holding said arms in box engaging position at the bottom of their travel, means causing said arms to separate at the upper limit of their movement, stack supporting arms pivotally mounted on said supporting plates, means normally urging said last mentioned arms to box engaging position, means whereby said supporting arms are separated by an ascending box passing therebetween, timing mechanism operable step by step to cause said lifting plates to reciprocate until a desired number of boxes has been stacked, discharge conveyor chains at the stacking station and disposed below said table rollers and adapted to receive a stack of boxes, said timing mechanism including means operable when the lowermost box of a stack has been placed in position on the table rollers to cause downward movement of the first set of plates to lower said last placed box onto the discharge conveyor and means operated by downward movement of said first pair of plates to cause said stack supporting arms to be withdrawn from beneath the stacked boxes to cause the stack to descend onto the box thereunder.

18. In a box stacking apparatus, spaced feed conveyor chains, a set of box conveying rollers adjacent to said chains and adapted to receive boxes from said chains, a box stacking station adjacent to and at one side of said rollers, a pair of supporting plates at said station, means to mount said plates for vertical reciprocation, a table forming frame supported by said plates, a set of rollers on said table forming frame, means for engaging a box on said conveying rollers and for moving said box axially along the conveying rollers onto the table forming rollers, a pair of lifting arms, means to reciprocally mount said lifting arms at each end of a box at the stacking station, said arms having inwardly directed lips adapted to engage beneath a box at the stacking station, means to alternately raise and lower said lifting arms, means normally holding said arms in box engaging position at the bottom of their travel, means causing said arms to separate at the upper limit of their movement, stack supporting arms pivotally mounted on said sup-

porting plates, means normally urging said last mentioned arms to box engaging position, means whereby said supporting arms are separated by an ascending box passing therebetween, timing mechanism operable step by step to cause said lifting plates to reciprocate until a desired number of boxes has been stacked, discharge conveyor chains at the stacking station and disposed below said table rollers and adapted to receive a stack of boxes, said timing mechanism including means operable when the lowermost box of a stack has been placed in position on the table rollers to cause downward movement of the first set of plates to lower said last placed box onto the discharge conveyor and means operated by downward movement of said first pair of plates to cause said stack supporting arms to be withdrawn from beneath the stacked boxes to cause the stack to descend onto the box thereunder.

19. In a box stacking apparatus, spaced feed conveyor chains, a set of box conveying rollers adjacent to said chains and adapted to receive boxes from said chains, a box stacking station adjacent to and at one side of said rollers, a pair of supporting plates at said station, means to mount said plates for vertical reciprocation, a table forming frame supported by said plates, a set of rollers on said table forming frame, means for engaging a box on said conveying rollers and for moving said box axially along the conveying rollers onto the table forming rollers, a pair of lifting plates, means to reciprocally mount said lifting plates at each end of a box at the stacking station, a pivoted box lifting arm carried by each of said lifting plates, each of said arms having an inwardly directed lip adapted to engage beneath a box at the stacking station, means to alternately raise and lower said lifting plates to thereby alternately raise and lower said arms, means normally holding said arms in box engaging position at the bottom of the travel of the lifting plates, means causing said arms to separate at the upper limit of their movement, stack supporting arms pivotally mounted on said supporting plates, means normally urging said last mentioned arms to box engaging position, means whereby said supporting arms are separated by an ascending box passing therebetween, timing mechanism operable step by step to cause said lifting plates to reciprocate until a desired number of boxes has been stacked, discharge conveyor chains at the stacking station and disposed below said table rollers and adapted to receive a stack of boxes, said timing mechanism including means operable when the lowermost box of a stack has been placed in position on the table rollers to cause downward movement of the first set of plates to lower said last placed box onto the discharge conveyor and means operated by downward movement of said first pair of plates to cause said stack supporting arms to be withdrawn from beneath the stacked boxes to cause the stack to descend onto the box thereunder.

20. In a box stacking apparatus, a box stacking station, means for moving a box to the station, a lifting arm reciprocally mounted at each end of a box at the station and mounted to move to and from box engaging position, means to alternately raise and lower said lifting arms, means for moving said arms to and from box engaging position, a pair of stack supporting arms at the station, means to mount said stack supporting arms for movement to and from box supporting position, means urging said supporting arms to box supporting position, means to cause said lifting arms

17

to release a box when in position to be engaged by the supporting arms, timing mechanism to cause said lifting arms to reciprocate until a desired number of boxes has been stacked, a discharge conveyor disposed at said station and adapted to receive a stack of boxes, said timing mechanism including means operable when the lowermost box of a stack is at the station to cause said stack supporting arms to lower the formed stack onto the discharge conveyor and means to cause said stack supporting arms to move to releasing position.

AMBROSE A. NEJA.
